UNITED STATES PATENT OFFICE.

FRED H. FERRIS, OF WILMINGTON, DELAWARE.

MODULATOR.

1,382,493.

Specification of Letters Patent. Patented June 21, 1921.

Application filed December 20, 1918. Serial No. 267,690.

To all whom it may concern:

Be it known that I, FRED H. FERRIS, a citizen of the United States, residing at 1400 Harrison street, Wilmington, in the county of New Castle and State of Delaware, have invented new and useful Improvements in Modulators, of which the following is a specification.

The invention relates to talking machines, also known as phonographs, and has for an object to provide a talking machine and modulator for varying or modulating the tones or sounds produced in the operation of the machine.

15 The invention comprehends, among other features, a modulating device which is so arranged and incorporated with the construction of the tone conveyer and amplifier, that the tones and sounds produced can be increased or decreased in volume by the mere operation of a suitable lever or other operating element provided, in conjunction with a pallet, to bring about an increase or decrease of the area of the throat of the 25 tone or sound conveyer.

I am aware that various kinds of modulating devices have been employed heretofore in connection with talking machines, for the purpose of modulating the tones and sounds produced, but in a majority of these instances, the pallet or modulating device consists of a flat disk or plate disposed in the sound conveyer or amplifier in such a manner that when it is desired to diminish 30 the volume of sound or tone, the disk or plate is arranged to choke or partially choke the tone conveyer or amplifier. Similarly the modulation of the tones of a talking machine has been carried out by partially or 35 entirely closing the larger end of the amplifier, through the medium of doors or slides. This latter form of arrangement however, again is but a choking off of the sounds and tones produced.

45 In my construction I aim to provide a modulating device which is so arranged that the modulation of the tones produced will be accomplished without the interposition, in the path of the sound, of any kind of an 50 obstruction, the design, construction and arrangement of my apparatus being based somewhat upon the principle of the restriction or modulation of the human voice, as it would issue from the throat and mouth 55 of the producer.

In the further disclosure of the invention,

reference is to be had to the accompanying drawings, constituting a part of this specification, in which similar characters of reference denote corresponding parts in all the views, and in which,

Figure 1 is a fragmentary vertical sectional view taken through a talking machine, showing my construction applied thereto, parts being broken away to disclose the underlying structure with the modulator plate or element shown in full lines in one position and dotted lines in another position.

Fig. 2 is a fragmentary horizontal sectional view taken substantially on the line 2—2 in Fig. 1, looking in the direction of the arrow.

Fig. 3 is a fragmentary vertical sectional view taken through a slightly modified form of my invention, and

Fig. 4 is a horizontal sectional view taken on the line 4—4 in Fig. 3.

Referring more particularly to the views, the numeral 10 indicates a talking machine comprising the usual cabinet 11 on which is mounted a swinging tone arm 12, carrying a reproducer 13, to which is attached a needle or stylus 14 adapted to operate over a record 15, mounted to rotate with a turntable 16.

In the make-up of the cabinet 11 there is formed a chamber 17 in which is arranged a horn or amplifier 18 having an end 19 open to the exterior of the cabinet. In the present instance I provide a sound conveyer 20, which consists of a vertically disposed tube 21 flared at its lower end and formed with the sound or tone conveyer, is the inner restricted end of the amplifier 18. It will of course be understood that the tone conveyer and amplifier can be made in two parts and bolted together or otherwise connected, this being an obvious expedient.

At the juncture of the tone conveyer 20 and amplifier 18, there is formed a pocket 22, an extended off-set portion 23 of the amplifier forming one part or side of the pocket and a downwardly extended portion 24 of the tone conveyer, forming another part or side of the pocket, with the portion 24 having an opening 25. A pallet or modulator element 26 is mounted to swing upon the tone conveyer at 27 and is arranged to back up against the opening 25, said modulator element being movable by means of a lever 28 into the position shown in dotted

lines, or into any intermediate position between those which are shown in dotted and full lines.

It will now be noted that the modulator element does not restrict the normal passage of the sound from the tone arm 12, through the tone conveyer 20 into the amplifier 18, but by adjusting the modulator element to increase or decrease the size of the off-set pocket 22, the modulation of the sounds produced, is accomplished and the sounds can be changed from their normal reproduction to diminish in volume at the will of the operator of the lever 28. Thus when the modulator element is in the position shown in dotted lines the normal reproduction, consistent with the size of the amplifier, takes place. Should it be desired to modulate the tone and bring about that diminishing effect, that oftentimes in certain reproductions is much desired, it is only necessary to swing the modulator element 26 toward the position in which it is shown in full lines to accomplish the desired result. It will therefore be apparent that the desired diminishing effect is accomplished without interposing in the normal path of the sound travel, any form of obstruction and that the desired result is brought about by increasing or decreasing the area of the pocket, or in other words, lengthening or shortening the depth of the tone conveyer.

In Figs. 3, 4, I disclose a modified form, in which the tone conveyer or tube is indicated by the numeral 30 and the amplifier by the numeral 31, the modulator element 32

being in the nature of a slide that can be moved upwardly or downwardly to increase or decrease the size of the offset pocket 33. To this end the modulator element is provided with a handle 34 and is guided in its movement by the extended side walls 35 and the walls 36.

It will be apparent that particularly in the case of the modulator element shown in the Figs. 1, 2, it is preferable to provide the inner face or side of the modulator element 26, with a lining 37 of some soft material such as felt, in order that a tight joint will be maintained at the point 38, where the modulator element slides along the extended side 23 of the pocket.

The structure described consists of few and simple parts and as mentioned heretofore, the device does not comprehend a choking up of the normal passage for the sound as it travels from the tone arm to and through the amplifier.

Having described my invention, I claim,—

A talking machine horn of right angular shape having its sides prolonged beyond the outer wall of the angle or elbow and having the outer wall of the elbow formed open, an arcuate plate pivoted at one edge of the opening, a curved wall extending outwardly from the horn at the opposite pivot point, said prolongations of the sides and said curved wall coöperating with said plate to form a pocket, and means for moving said plate whereby to vary the size of said pocket.

In testimony whereof I affix my signature.

FRED H. FERRIS.
